US00D647252S

(12) **United States Design Patent**
Green et al.

(10) **Patent No.:** US D647,252 S
(45) **Date of Patent:** ** *Oct. 18, 2011

(54) **GLOVE**

(75) Inventors: **David Green**, Toronto (CA); **Neal Ho**, San Francisco, CA (US)

(73) Assignee: **Duncan Kitchen Grips, Inc.**, Tustin, CA (US)

(*) Notice: This patent is subject to a terminal disclaimer.

(**) Term: **14 Years**

(21) Appl. No.: **29/381,979**

(22) Filed: **Dec. 27, 2010**

Related U.S. Application Data

(63) Continuation of application No. 29/355,481, filed on Feb. 8, 2010, now Pat. No. Des. 629,971.

(57) **CLAIM**

The ornamental design for a glove, as shown and described.

DESCRIPTION

This application is further related to the following U.S. Design Patent Applications: Ser. No. 29/355,477, which was filed on Feb. 8, 2010; Ser. No. 29/355,480, which was filed on Feb. 8, 2010; and Ser. No. 29/355,482, which was filed on Feb. 8, 2010.

FIG. 1 is a perspective view of our new design for a glove.

FIG. 2 is a front elevation view of the glove of FIG. 1.

FIG. 3 is a first side elevation view (outer side) of the glove of FIG. 1.

FIG. 4 is a second side elevation view (top side) of the glove of FIG. 1.

FIG. 5 is a third side elevation view (inner side) of the glove of FIG. 1.

FIG. 6 is a fourth side elevation view (bottom side) of the glove of FIG. 1; and,

FIG. 7 is a rear elevation view of the glove of FIG. 1.

In FIG. 1-7, the broken lines are included for the purpose of illustrating environment and form no part of the claimed design. The broken lines for the trademark "KG" are included for the purpose of illustrating environment and form no part of the claimed design. The broken line showing of the flap portion and of the stitching is for the purpose of illustrating portions of the glove and forms no part of the claimed design.
